UNITED STATES PATENT OFFICE.

MAX TAIGMAN, OF NEW YORK, N. Y.

STARTING-BOX.

1,149,003.

Specification of Letters Patent. Patented Aug. 3, 1915.

Application filed July 7, 1914. Serial No. 849,449.

To all whom it may concern:

Be it known that I, MAX TAIGMAN, a citizen of the United States, and a resident of the city of New York, borough of Manhattan, in the county and State of New York, have invented a new and Improved Starting-Box, of which the following is a full, clear, and exact description.

Among the principal objects which the present invention has in view are: to provide for discontinuing the supply of electric current when the retracting element of the switch lever becomes disabled; to provide for discontinuing the current supply when the back of the starting box is opened; to interrupt the current supply in the event the box cover becomes loosened; and to multiply the current-interrupting effects in the event of the retracting spring of the starting switch lever becoming disabled.

Drawings.—Figure 1 is a front elevation of a box of the character named, constructed and arranged in accordance with the present invention, showing the same in normal service relation; Fig. 2 is a like view showing the parts as disposed subsequent to the breaking of the retracting spring supporting the starting switch lever; Fig. 3 is an end view of the box as shown in Fig. 1 of the drawings; Fig. 4 is an end view of the box as shown in Fig. 2 of the drawings, the connecting plug being removed; Fig. 5 is a top plan view of the box disposed as shown in Fig. 1 of the drawings, one of the suspending legs being removed to expose the working parts below; Fig. 6 is a front view of a fragment of a box having a current-supply switch and retainer therefor, constructed and arranged in accordance with a modification of the invention; Fig. 7 is an end view of the box, equipped with a modified form of the current-supply switch constructed as shown in Fig. 6 of the drawings; Fig. 8 is an end view of the box, showing a further modified form of current-controlling switches therefor; Fig. 9 is a detail view, on an enlarged scale, showing a corner fragment of the body of the box, a corner fragment of the back of the box, and a fragment of the retainer for the current-supply switch.

Description.—As set forth in an application for patent upon improvements in starting boxes, No. 830,675, filed by me April 9, 1914; and in an application for patent upon improvements in starting boxes, No. 837,198,

filed by me May 8, 1914, the box cover 15 is shown and described as having a spring metal jumper 115, which electrically connects the terminal 110 and a corresponding terminal 114. These parts will be found in the application first above mentioned, having the numbers herein enumerated applied to the drawings in said application. These numbers are also applied in the present application. In the second of the above-mentioned applications, there is disclosed means embodying a Menchen or other plug for introducing the current supply directly to the coil terminals of the resistance unit. In the present invention, a Hubbel plug connector 16 is employed to receive terminal contacts 17 when forced thereover. Interposed in advance of the terminal contacts 17 is a ring 18, which ring is formed at the end of a pendent arm 19 pivotally mounted in a lug 20 constituting a portion of the casting of the leg 21 with which the box body 22 is furnished. The arm 19 and the ring 18 thereof are held, when in service position, adjacent the side of the box body 22 by a retaining arm 23, which is placed over a cam head 24. The cam head 24 and the arm 19 are pressed outward by the normal operation of a spring 25.

The lower end of the arm 19 is guided in its action by a pin 26, which passes through an enlarged perforation formed in the cross bar 27 of a yoke housing for the spring 25. The yoke housing referred to is formed by bending the arm 19 to the shape seen best in Fig. 1 of the drawings.

The retainer arm 23 is held in service position by a retracting spring 28. The retracting spring 28 is operatively connected with the starting switch lever 29 by a hook 30 formed on said switch lever. The opposite end of the spring 28 is anchored in an eyelet formed in a tab 31 of an arm 32 extending horizontally from the rocking bar 33. The rocking bar 33, retaining arm 23 and arm 32 are preferably constructed integrally. In like manner, an elongated loop 34 is provided to engage a dowel 35, by which the cover 15 is retained in closed position. This construction is best shown in Figs. 1 and 5 of the drawings.

The spring 28 is sufficiently powerful to hold the retaining arm 23 on the cam head 24 when the parts are in the position shown in Fig. 1. The exposed end of the lever 29 is rocked from the position shown in Fig. 1,

downward when current is being delivered to the motor. The tension on the spring 28, therefore, is not decreased until the same becomes weakened or is broken, as shown in 5 Fig. 2 of the drawings. The restraint on the spring 28 being thus relaxed or removed, the spring 25 is permitted to press outward the end of the arm 19 having the ring 18, to the position likewise shown in Fig. 2 of the 10 drawings. This movement is accompanied by the ring 18 stripping the connector 16 from the contacts 17. In time with the above action, the cam head 24 moves the arm 23 forward, and lifts the loop 34 from 15 engagement with the dowel 35. The immediate effect of this is to permit the jumper 115 to force the cover 15 outward to overbalance the same, causing it to rock on the spring latch 36. The jumper 115 is thereby 20 removed from the terminal 110, as best shown in Fig. 4 of the drawings.

The cover 15 is provided with side flanges 37, and with a top flange 38, which partially cover the opening to the box body 22 when 25 said cover is in the position shown in Fig. 4. This construction avoids the liability of damage incident to the introduction of any foreign matter into the box during the period when the local circuit therein is 30 broken in the manner described, and by the cover 15 assuming the position shown in Fig. 4 of the drawings. The cover 15 is arrested in the position shown in Fig. 4, by lugs 39 engaging pins 40, which project 35 from the side of the body 22.

The box body 22 is permanently covered by a removable back 41. The back 41 is held in service position by a screw bolt 42 and a nut 43. The back 41 performs the 40 further function of holding the bar 33 in recesses 44 formed in the rear edge of the legs 21, as best seen in Figs. 3 and 4 of the drawings. When the back 41 is released or removed, the pressure of the cam head 24 45 on one side, and the pull of the spring 28 on the arm 32 on the other side, co-operates to dislodge the bar 33 from the recesses 44, thereby releasing the arm 19 to permit the stripping of the connector 16 and the suspension of the current service for the starting box. Provision is thus made for the avoidance of accidents due to accidental or 50 careless dislodgment of the back 41 while electric current is being furnished thereto.

55 In the modified form shown in Figs. 6 and 7, a switch for the current supply, having a button 45, is employed. The button 45 is wedge-shaped, to furnish an inclined surface rest for the retaining arm 23, similar 60 to that furnished by the cam head 24 in the preferred form. The button and switch are contained within the conventional cap 46. The operation in the modified form is to 65 all intents and purposes identical with that of the preferred form, with the single ex-

ception that the button 45 is not separated from the structure to the same extent as is the connector 16 in the preferred form.

In Fig. 8 of the drawings, a further modification is shown, wherein a short retaining arm 47 is employed in lieu of the longer retaining arm 23. The arm 47 is furnished at the lower end thereof with a knife blade 48, adapted to extend between the blades 49 and 50 of electric-supply terminals. When 75 the retracting spring 28 is broken, a coil spring 51, which is anchored to the end of the blade 48 and to a pin 52 set out from the side of the body 22, draws said blade out of contact with the blades 49 and 50. 80

Claims:

1. A starting box comprising a switch lever; an electric current supply, embodying a removable connector; a retainer holding said connector in service position; and a 85 retractor for said lever operatively connected with said retainer to normally hold the same in service position.

2. A starting box comprising a switch lever; an electric current supply, embodying a removable connector; a retainer holding 90 said connector in service position; a retractor for said lever operatively connected with said retainer to normally hold the same in service position; and means for 95 disengaging said retainer and said connector.

3. A starting box comprising a switch lever; an electric current supply, embodying a removable connector; a retainer holding 100 said connector in service position; a retractor for said lever operatively connected with said retainer to normally hold the same in service position; and means for removing said connector from service position 105 when said retractor fails to support said lever.

4. A starting box comprising a switch lever; an electric current supply, embodying a removable connector; a retainer holding 110 said connector in service position; a retractor for said lever operatively connected with said retainer to normally hold the same in service position; means for removing said connector from service position 115 when said retractor fails to support said lever; and an inclined seat for said retainer mounted on said connector.

5. A starting box comprising a containing box body; a switch lever; an electric 120 current supply embodying separable terminals disposed within said box body; a removable cover for said box body, said cover forming a support for one of said terminals; a retainer for said cover, holding the same 125 in service position; and a retractor operatively connecting said retainer and said lever to hold both in service position.

6. A starting box comprising a containing box body; a switch lever; an electric 130

current supply embodying separable terminals disposed within said box body; a removable cover for said box body, said cover forming a support for one of said terminals; a dowel mounted on said cover to hold the same in position; a spring latch to coöperate with said dowel, for holding said cover; a retainer having an opening to removably engage said dowel; and a retractor operatively engaging said retainer and lever, for holding the same in operative position.

7. A starting box comprising a box body

portion; an electric current supply; a removable connector for said supply; a retainer for said connector, embodying a rocking bar; and a removable back for said box body, adapted to form a bearing for said rocking bar.

In testimony whereof I have signed my name to this specification in the presence of two subscribing witnesses.

MAX TAIGMAN.
